CLEVE T. SHAFFER, OF SAN FRANCISCO, CALIFORNIA.

DUST-GUARD FOR VALVE-STEMS.

1,191,840.

Specification of Letters Patent. Patented July 18, 1916.

Application filed April 15, 1913, Serial No. 761,295. Renewed February 15, 1916. Serial No. 78,550.

To all whom it may concern:

Be it known that I, CLEVE T. SHAFFER, a citizen of the United States, residing at the city and county of San Francisco and State of California, have invented certain new and useful Improvements in Dust-Guards for Valve-Stems, of which the following is a specification.

The hereinafter described invention relates to improvements in dust caps as used in connection with the valve stems of pneumatic tires, and the invention has for its principal objects to provide an improved dust cap the employment of which will obviate the necessity of screwing the cap on and off of the valve stem as is now the custom; to provide a dust cap having yieldable means which is so arranged that when the cap is in position on the valve stem that the same will frictionally engage the stem and retain the protector thereon, and provide a hermetic seal around the valve stem; and to provide a dust cap which is simple in construction, consists of but few parts, and one which is thoroughly efficient for the purposes designed.

In vehicles where pneumatic tires are used the valve stem which is threaded for its full length extends through an opening in the felly and is retained in position therethrough by a threaded washer and is protected from the weather and injury by a threaded dust cap engaging the valve stem threads and screwed down on the stem for its entire distance and the operation of attaching and removing the cap and washer is tedious and slow owing to the necessity of threading the parts for the full length of the valve stem.

The present invention relates to improvements in devices for positioning over the valve stem to protect the same from injury and to retain the same in position, and one which may be quickly removed from or applied to the valve stem and without screwing the same for the full length thereof and when once in position on the valve stem will not shake loose.

With the above mentioned and other objects in view, the invention consists in the novel construction and combination of parts hereinafter described, illustrated in the accompanying drawings, and pointed out in the claims hereto appended; it being understood that various changes in the form, proportion, size and minor details of construc-

tion, within the scope of the appended claims, may be resorted to without departing from the spirit or sacrificing any advantages of the invention.

To more fully comprehend the invention, reference should be had to the accompanying sheet of drawings, wherein is disclosed one form of my invention, and in which—

Figure 1 is a view in elevation of a section of a pneumatic tire with my improved dust cap positioned over the valve stem thereof. Fig. 2 is a vertical sectional view disclosing the two members forming the dust cap and the portion of flexible material interposed between and acted on by the members. Fig. 3 is a vertical sectional view disclosing the manner of mounting and retaining the dust cap on the valve stem.

Referring more particularly to the drawings, the reference numeral 1 designates the externally threaded valve stem of a pneumatic tire which is preferably retained in position through the felly by the nut 2 and is normally closed at its open end by the valve cap 3, of any well known type.

My improved dust guard comprises the elongated tubular receiving member or cap 4 closed at its upper end, as at 5, and formed at its opposite end with an outwardly flaring, inclined, annular flange wall 6, which terminates in an annular collar or sleeve 7 threaded on its lower inner surface and knurled on its outer surface, as at 8, the walls of the annular collar or sleeve being substantially parallel to the walls of the tubular member 4, and said cap is adapted for positioning over the upper portion of the valve stem 1. The threaded collar or sleeve 7 is adapted for receiving the upper exteriorly threaded portion 9 of an open ended tubular member or washer 10 formed with a knurled annular flange 11, and provided on its interior surface with an annular cut away portion or seat 12 opening at the top of the member or washer 10.

A suitable flexible tubular packing or gripping member 13, preferably formed of rubber, is seated in the cut away portion or seat 12, and the upper end 14 of said packing extends above the upper end of the member or washer 10, and is adapted when the members 4 and 10 are positioned over the valve stem and drawn together, to contact with the inner surface of the outwardly flaring flange wall 6 and be forced inwardly thereby, frictionally engaging the surface

of the valve stem 1 retaining the members thereon and forming a hermetical seal around the valve stem to prevent the escape of any air from the valve stem, should the 5 valve cap 3 become dislodged.

From the above description, it will be apparent that the members 4 and 10 when in slight threaded engagement do not force the packing 13 inwardly, as is shown in Fig. 2, 10 and that the structure is capable of being readily positioned over and removed from the valve stem, but that when it is desired to prevent displacement of the structure from the valve stem it is only necessary to advance the members toward each other until 15 such time as the upper end 14 of the packing contacts with the annular incline 6 which will force the packing inwardly against the valve stem 1, as in Fig. 3, and retain the dust 20 guard in position. To remove the dust guard it is only necessary to give the members a slight twist which, through the threaded portions thereof, will cause the same to separate and the inclined flange wall 6 to disengage from the upper edge of the packing, 25 which will permit the packing to assume the position as in Fig. 1, and admit of the dust guard being readily removed therefrom without the necessity of rotating the same 30 for the full length of the valve stem as is the case with the structures now employed.

While the nut 2 is disclosed as having been positioned to secure the valve stem in place, it is to be understood that this nut 35 may be dispensed with and the tubular member or washer may rest on the felly and in this way supplant the nut.

Having thus described my invention what I claim and desire to protect by Letters 40 Patent is—

1. A quickly detachable dust guard for threaded valve stems, comprising a tubular member for loosely positioning over the valve stem, a dust cap associated with said 45 tubular member and adapted for loosely positioning over and for inclosing said stem, an annular flexible gripping member interposed between said tubular and dust cap members and through which said stem extends, and a means carried by said cap and tubular members whereby the same may by a relative rotary movement be drawn together for forcing said gripping member into engagement with the valve stem to detachably 50 secure the tubular member and dust cap.

2. A quickly detachable dust guard for threaded valve stems, comprising a tubular member for loosely positioning over the 55 valve stem and through which the stem extends, a cap associated with said tubular member and adapted for loosely positioning over and for inclosing said stem, an annular flexible gripping member carried by one of said members and adapted to be engaged by

the other of said members, and a threaded connection between said cap and tubular member whereby the same may by a rotary movement be drawn together for forcing said gripping member into engagement with 70 the valve stem to detachably secure said tubular member and dust cap thereto and to provide a seal surrounding said stem below the open end thereof.

3. A quickly detachable dust guard for 75 threaded valve stems, comprising a tubular member for loosely positioning over the valve stem and through which the stem extends, a dust cap associated with said tubular member and adapted for loosely positioning over said stem, an annular flexible gripping member carried by said tubular member and through which the valve stem extends, one end of said gripping member projecting beyond said tubular member, a 80 threaded connection between said cap and tubular member for adjusting the same by a rotary movement relative to each other, and means carried by said cap for contacting with the projecting end of the said gripping member to force the same into engagement with the valve stem when the tubular member and cap are drawn together to detachably secure said tubular valve and dust cap to said stem. 85

4. A quickly detachable dust guard for 90 threaded valve stems, comprising a tubular member or washer for loosely positioning over the valve stem, a dust cap for loosely positioning over the valve stem and coöperating with the tubular member, and a flexible member within said dust cap for engaging the valve stem to detachably secure the cap and tubular member or washer thereto on the drawing of said tubular member or washer and said dust cap together by a relative rotary movement thereof. 95

5. In combination with a threaded valve 100 stem, coöperating tubular dust cap and washer members for simultaneous loose positioning over the valve stem, and a yieldable member adapted on the drawing together of said tubular dust cap and washer members upon a relative rotary movement thereof for engaging the valve stem to detachably secure 105 said dust cap and washer members thereto. 110

6. A quickly detachable dust guard for 115 threaded valve stems, comprising a yieldable member for loosely positioning over the valve stem, a tubular member or washer for loosely positioning over the valve stem and having an interior tapered surface for receiving said yieldable member, and a dust cap for loosely positioning over the valve 120 stem in coöperative relation with the tubular member or washer and adapted by a relative rotary movement thereof on the drawing together of said tubular member or washer and said dust cap for forcing said yieldable member into engagement with the valve 125

130

stem to detachably secure the dust cap and tubular member or washer thereto.

7. A quickly detachable dust guard for threaded valve stems comprising a tubular member or washer and a cooperating dust cap member both adapted for loose positioning on the valve stem, a yieldable gripping member interposed between said mentioned members and forced into engagement with the valve stem by a relative rotary movement thereof and the movement toward each other of the tubular member and dust cap to detachably secure the dust cap and tubular member or washer thereto.
15. 8. A quickly detachable dust guard for threaded valve stems, comprising a tubular member or washer and a cooperating dust cap adapted for loosely positioning over the valve stem, one of said members provided with an interior tapered portion, and a yieldable gripping member carried by the other member and adapted for engaging the valve
- stem to detachably secure the dust cap and tubular member or washer thereto on the relative rotary movement of said tubular member or washer and dust cap toward each other.
9. A quick detachable dust guard for threaded valve stems comprising a stem inclosing and dust excluding member into which the valve stem freely passes, an associated member through which the valve stem freely passes, and means operated by a relatively rotary movement of the said two members for securing the guard on the valve stem.

In testimony whereof I have signed my name to this specification in the presence of two subscribing witnesses.
